CLAIM

The ornamental design for a work light, as shown and described.

DESCRIPTION

FIG. 1 is a front-bottom perspective view of a work light, showing my new design;

FIG. 2 is a rear-top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines in FIGS. 1-8 show portions of the work light that form no part of the claimed design.
